ALBERT J. BATES, OF CHICAGO, ILLINOIS, ASSIGNOR TO BATES EXPANDED STEEL TRUSS CO., OF WILMINGTON, DELAWARE, A CORPORATION OF DELAWARE.

ROTARY SHEARS.

1,272,891.

Specification of Letters Patent. Patented July 16, 1918.

Application filed December 22, 1915. Serial No. 68,145.

To all whom it may concern:

Be it known that I, ALBERT J. BATES, a citizen of the United States, residing at Chicago, in the county of Cook and State of Illinois, have invented certain new and useful Improvements in Rotary Shears, of which the following is a specification.

This invention relates to the art of metal working and more particularly to a machine 10 adapted for use in shearing metal, such for example as steel members which are to be subsequently expanded as described in a Patent No. 1,005,925, granted to me on October 17, 1911, although obviously my invention is in no way limited to the treatment of metal for this specific purpose.

In developing the invention disclosed in my above-mentioned patent I discovered that no means was available for rapidly and 20 efficiently shearing cold metal in the manner required for the accomplishment of my purpose.

It is the object, therefore, of my invention to provide a rotary shear which is substantial, 25 powerful and rapid in operation and which is well adapted for use in shearing cold metal of considerable thickness.

A further object of my invention is the provision of means whereby a plurality of 30 longitudinally spaced slits may be made in the metal without causing undue strains therein and for replacing the displaced metal in its original plane after the shearing operation.

35 A still further object of my invention is the provision of means whereby a plurality of laterally spaced slits may be made in the metal and whereby lateral thrust of the shear elements is neutralized.

40 Another object of my invention is to provide means for shearing metal sections to produce a plurality of longitudinally and laterally spaced slits of progressively varying length so that when expanded the truss 45 elements thus formed will vary in length and the section in its final form will be longitudinally tapered.

Further objects of my invention are the provision of simple and effective means for 50 driving the mechanism, means for establishing a driving connection at will and for automatically breaking the driving connection at intervals and means for preventing the establishment of a driving connection under 55 certain conditions.

Other objects and advantages of my invention will be apparent as it is better understood by reference to the following specification when read in connection with the accompanying drawing illustrating a preferred embodiment thereof, in which—

Figure 1 is a vertical section through the supporting frame and illustrates the shear in side elevation;

Fig. 2 is an enlarged side elevation partially in section, illustrating the driving and feeding means;

Fig. 3 is a vertical section on the line 3—3 of Fig. 2;

Fig. 4 is a vertical section on the line 4—4 of Fig. 1;

Fig. 5 is an enlarged plan view of the driving mechanism for the shear with parts in section;

Fig. 6 is a vertical section on the line 6—6 of Fig. 5;

Fig. 7 is an end elevation of the shear and its supporting frame and the driving mechanism;

Fig. 8 is an enlarged vertical section on the line 8—8 of Fig. 7;

Fig. 9 is a vertical section on the line 9—9 of Fig. 8;

Fig. 10 is a vertical section on the line 10—10 of Fig. 11 and illustrates the shear 85 elements on an enlarged scale and the manner in which they are secured to the rotary shear members;

Fig. 11 is a vertical section on the line 11—11 of Fig. 10;

Fig. 12 is a plan view of a portion of a metallic member after the shearing operation;

Fig. 13 is a development of the face of the lower shear member;

Fig. 14 is a similar view of the face of the upper shear member;

Fig. 15 is a vertical section on the line 15—15 of Fig. 10, and

Fig. 16 is a vertical section on the line 16—16 of Fig. 10.

Referring to the drawing, 1 indicates a foundation, preferably of concrete, providing a pit beneath the floor 2 in which a portion of the structure is located so that the operative parts are disposed at a convenient level above the floor. A supporting frame is provided comprising the uprights 3, a horizontal member 4 and braces 5 to support the shear.

Journalized in suitable bearings 6 in the uprights 3 are a pair of shafts 7 to which are secured the rotary shear members 8 and 9 carrying shear elements on their peripheries as will presently be described. The rotary shear members 8 and 9 are also provided on their peripheries with interengaging gear teeth 10, whereby they are caused to rotate at the same peripheral speed when

10 one of the rotary shear members is driven from a source of power.

A source of power, such for example as a motor 11 (Fig. 5), is mounted on the foundation 1 adjacent the shear and drives a shaft 12, journalized in suitable bearings 13 through the pinion 14 on the motor shaft 15 and the gear 16 secured to the shaft 12. A pinion 17 is loosely mounted on the shaft 12 and meshes with a gear 18 secured to a shaft 19 journalized in bearings 20. A pinion 21, secured to shaft 19, meshes with the teeth 10 on the rotary shear member 9 and drives the shear members 8 and 9 when the shaft 19 is rotated.

25 To establish a driving connection between the motor 11 and the shear members 8 and 9 I provide a clutch 22 splined to the shaft 12 and slideable longitudinally thereof, the clutch 22 being provided with teeth 23 adapted to mesh with teeth 24 formed on the pinion 17. The clutch 22 is connected to one arm of a lever 25 pivotally mounted at 26 on an arm 27 secured to the beam 35' forming a part of the frame. Adjacent the clutch 22 a bar 28 is pivotally connected by means of a pin 29 to the lever 25 and a spring 30, connected to the bar 28 and to a bracket 31, mounted on the foundation 1, tends to move the bar 28 and the lever 25 into position to cause engagement of the teeth 23 of the clutch 22 with the teeth 24 of the pinion 17. The opposite end of the bar 28 is provided with a notch 32 which is normally engaged by the end of a lever 33 pivotally mounted at 34 on a bracket 34' secured to the beam 35' and is provided at its opposite end with a roller 35 adapted to cooperate with a cam 36 secured to the side of the rotary shear member 9 (Fig. 6.) A spring 37, secured to the bar 28 and to the bearing 13, draws the bar 28 into engagement with the end of the lever 33 and a spring 38 secured to the lever 33 and to the beam 35' maintains the roller 35 in engagement with the rotary shear member 9. As will be readily understood, when the roller 35 rides onto the cam 36 during the rotation of the rotary shear member 9 the lever 33 will turn on its pivot 34 and by reason of its engagement with the notch 32 in the bar 28 will turn the lever 25 on its pivot 26 and withdraw the teeth 23 of the clutch 22 from the teeth 24 of the pinion 17, thus breaking the driving connection.

65 To insure the immediate stopping of the

rotary shear members 8 and 9 when the driving connection is broken I provide a brake comprising a spider 39 slidably mounted on the shaft 19 and pivotally connected at 40 to one end of the lever 25. Brake shoes 41, cooperating with the inner periphery of the gear 18, are connected to the arms 42 of the spider 39 by links 43 and when the lever 25 turns about its pivot 26 to withdraw the teeth 23 of the clutch 22 from engagement with the teeth 24 of the pinion 17 the brake shoes 41 will be forced into engagement with the inner periphery of the gear 18 to stop the mechanism.

To release the notch 32 on the bar 28 from engagement with the lever 33 and establish a driving connection from the motor 11 to the rotary shear member 9 I provide a foot lever 44 (Fig. 1) pivotally mounted at 45 on a bracket 46 secured to the base 1 and 85 provided with an arm 47 which is connected by a link 48 to a lever 49 pivotally mounted at 50 on one of the uprights 3. The opposite end of the lever 49 is connected by a link 51 to the bar 28 at 52. When the foot lever 90 44 is actuated the lever 49 is turned on its pivot 50 and through the link 51 draws the end of the bar 28 away from the end of the lever 33 so that it disengages the notch 32 on the bar 28, whereupon the 95 spring 30 turns the lever 25 on its pivot 26 to engage the teeth 23 of the clutch 22 with the teeth 24 of the pinion 17, the brake shoes 41 being simultaneously withdrawn from engagement with the inner periphery of the 100 gear 18. As soon as the roller 35 is released from the cam 36 the end of the lever 33 will be moved by the spring 38 to reengage the notch 32 so that when the rotary shear member 9 has made a complete rotation and 105 the roller 35 has again engaged the cam 36 the mechanism will be operated as previously described to break the driving connection.

The means for feeding material to be 110 sheared to the rotary shear members 8 and 9 comprises an elongated supporting member 53 mounted on suitable brackets 54, which are in turn supported on an I-beam 55 forming a part of the frame of the machine. A chain housing 56 is secured to the support 53 and within the housing a conveyer chain 57, provided with an upstanding lug 58 on one of its links, is mounted, the chain being disposed at either end over suitable sprockets 59, one of which is loosely mounted on a shaft 60 mounted in suitable bearings above the shaft 19. A gear 61 is secured to the shaft 60 and meshes with a pinion 62 on the shaft 19, the gear 61, pinion 120 62 and sprocket 59 being so proportioned as to advance the chain 57 at a rate equivalent to the peripheral speed of the rotary shear members 8 and 9. In order, however, to provide for any slight differences in speed, 130

which may result from variations in the thickness of the material sheared I provide a lost motion connection between the shaft 60 and the sprocket 59 comprising a member 63 secured to the shaft 60 and provided with flanges 64, and springs 65 disposed between the flanges 64 and similar flanges 66 on the sprocket 59. Bolts 67 connect the flanges 64 and 66 and prevent relative movement thereof in one direction. As will be apparent from the foregoing description, any retardation of the chain 57, owing to decreased peripheral speed of the rotary shear members 8 and 9, will result in a compression of springs 65 and no injury to the mechanism can result.

In suitable bearings 68 adjacent the delivery side of the rotary shear members 8 and 9 I mount a pair of shafts 69 and 69' to each of which is secured a roll 70 which rolls are adapted to coöperate with the sheared material as it leaves the rotary shear members 8 and 9 for a purpose presently to be described. On either side of the rolls 70 flange guides 71 (Fig. 9) are mounted which guides are adapted to coöperate with the flanges of the sheared material to maintain them in proper relative position. Collars 72 are mounted on the shafts 69 and 69' on either side of the flange guides 71 and provide for adjustment of the flange guides 71 in accordance with the width of the flanged structural members which are passed through the machine. Intermeshing pinions 73 are secured to the shafts 69 and 69' and a gear 74 is secured to the shaft 69 and meshes with a pinion 75 running loose on a stationary pin 76. A sprocket 77 is secured to the pinion 75 and a chain 78 connects the sprocket 77 with the sprocket 79 on the shaft 12, the various parts being proportioned so that the peripheral speed of the rolls 70 is equal to the peripheral speed of the rotary shear members 8 and 9. It may be noted that the rolls 70 are continuously driven when the mechanism is in operation.

Adjacent the rolls 70 is a table comprising uprights 80 and a horizontal member 81, to which are secured brackets 82 supporting rollers 83 to receive the sheared material as it is released from the rolls 70. To prevent the actuation of the foot lever 44 to establish a driving connection between the motor 11 and the rotary shear members 8 and 9 when sheared material remains in position on the rollers 83, I provide a safety device comprising a bell-crank lever 84 pivotally mounted at 85 on the horizontal member 81, one arm 86 of which is connected by a link 87 to the lever 49 (Fig. 1). The other arm of the bell-crank lever is adapted to engage the material on the rolls 83 so that the foot lever 44 can not be depressed until the sheared material has been removed from the rollers 83.

The rims of the rotary shear members 8 and 9 are rabbeted (Fig. 11) to provide a support for the shear elements 88, of hardened steel. The shear elements 88 are supported on thrust plates 89 which engage the peripheries of the rotary shear members 8 and 9 and the shear elements 88 and thrust plates 89 are held in position between clamping plates 90 and securely fastened to the peripheries of the rotary shear members 8 and 9 by bolts 91, the heads of which engage circular slots 92 in the peripheral portion of the rotary shear members 8 and 9. Clamps 93 are disposed between the outer clamping plates 90 and the nuts 94 of the bolts 91. This arrangement maintains the shear elements 88 rigidly in the desired position and transmits the shearing forces directly to the rotary shear members 8 and 9.

In carrying out the desired object of shearing structural members for the purpose specified in my above-mentioned patent it is necessary to provide for cutting a plurality of parallel lines of slits 95 (Fig. 12) in the web of the member, the slits being spaced longitudinally and staggered so that intact portions 96 appear in similar relation throughout the entire length of the sheared member. The shear elements 88 on the lower rotary shear member 9 are, therefore, separated by filler blocks 97, so that the inner faces of the shear elements 88 on the lower rotary shear member 9 are substantially in the plane of the outer faces of the shear elements 88 on the upper rotary shear member 8, the latter shear elements being disposed in abutting relation. This arrangement has an advantage in that the lateral forces which normally would tend to separate the opposed shear elements, when shearing pressure is exerted thereon, are neutralized or balanced and hence I am able to shear cleanly through material of considerable thickness without danger of distorting the metal or breaking the shear elements. As has previously been stated, it is necessary that the slits 95 be staggered and accordingly the shear elements 88 are arranged in staggered relation on both of the rotary shear members 8 and 9, as will be clearly understood by reference to Figs. 13 and 14.

The mode of operation of my invention should be apparent from the foregoing without further description of the structure thereof. A flanged structural member 98 to be sheared is disposed upon the supporting member 58 and the foot lever 44 is depressed to establish a driving connection between the motor 11 and the remainder of the mechanism in the manner previously described. The lug 58 engages the end of the structural member 98 and moves it into the bite between the shear elements 88 on the rotary shear members 8 and 9. As the member 98 advances the opposed shear elements

88 shear and displace the metal as indicated in Figs. 15 and 16, Fig. 15 illustrating the action at a point where the slits 95 overlap and Fig. 16 illustrating the action at one of the intact portions 96. The member 98 continues until it engages the rolls 70 which serve to return the displaced metal to its normal plane so that, when the operation is completed and the member 98 rests upon the rollers 83, the web of the member 98 will present its normal flat appearance but with the staggered slits 95 therein. In putting my invention into practice I have discovered that it is not practicable to so arrange the shear elements 88 that they meet during the shearing operation, as has heretofore been the common practice in the operation of shears for the reason that the displacement of the metal would be so great as to strain the intact portion 96 to an extent which would either rupture the metal or so weaken it that it is useless. I have discovered, however, that in treating non-fibrous metal, such as steel, it is possible to shear cleanly through the metal without causing the shear elements to meet, it being sufficient in fact for the shear elements to approach each other as closely as one-half of the thickness of the metal to be sheared. I have, therefore, arranged the rotary shear members 8 and 9 so that the opposed shear elements 88 thereon are spaced diametrically of the rotary shear members 8 and 9 a distance equal to approximately one-half of the thickness of the metal which the machine is designed to treat. Under this condition the displacement of the metal during the shearing operation is not sufficient to in any way endanger the intact portions 96, but, owing as before stated to the non-fibrous nature of the material, the metal is cleanly sheared and the slits 95 are formed without the necessity of causing the shear elements 88 to meet. The rolls 70 have an additional function in this connection in that should the shear elements 88 fail to break all of the fibers during the shearing operation the doubling back of the fibers as the metal passes between the rolls 70 will insure that the fibers are broken so that by no possibility can a member 98 come from the machine with the portions which should be slotted intact.

From the foregoing it will be apparent that I have perfected a machine which presents numerous features of novelty over the prior art and which is peculiarly adapted to perform a desired function in a novel and extremely desirable manner and with sufficient rapidity to meet the commercial conditions which surround the treatment of metallic structural members for the uses for which they are intended.

It will be further apparent that various changes may be made in the form, construc-

tion and arrangement of the parts without departing from the spirit and scope of the invention or sacrificing any of its material advantages, the form hereinbefore described being merely a preferred embodiment thereof.

70 I claim:

1. A machine for shearing cold metal, comprising a frame, a pair of members rotatably supported thereon, and shear elements mounted on the peripheries of said members to coöperate as said members are rotated, the axes of said members being so disposed that the shear elements on the respective members are spaced apart a distance substantially equal to one half the thickness of the material sheared, at a line joining said axes.

75 2. A machine for shearing cold metal, comprising a frame, a pair of members rotatably supported thereon, and a plurality of individual shear elements secured to the peripheries of said members and adapted to coöperate as said members are rotated to shear in a plurality of parallel lines, the axes of said members being so disposed that the shear elements on the respective members are spaced apart a distance substantially equal to one-half the thickness of the material sheared, at a line joining said axes.

80 3. A machine for shearing cold metal, comprising a frame, a pair of members rotatably supported thereon, and a plurality of sets of circumferentially spaced individual shear elements secured to the peripheries of said members and adapted to coöperate as said members are rotated to shear in a plurality of parallel lines, the axes of said members being so disposed that the shear elements on the respective members are spaced apart a distance substantially equal to one half the thickness of the material sheared, at a line joining said axes.

85 4. A machine for shearing cold metal comprising a frame, a pair of members rotatably supported thereon, and a plurality of sets of circumferentially spaced individual shear elements arranged in staggered relation on each of said rotatable members and adapted to coöperate as said members are rotated to shear in a plurality of parallel lines in which the slits, formed in the material sheared, are spaced longitudinally and staggered, the axes of said members being so disposed that the shear elements on the respective members are spaced apart a distance substantially equal to one half the thickness of the material sheared, at a line joining said axes.

90 5. A rotary shear comprising a frame, a pair of members rotatably supported thereon, a source of power, means for operatively connecting said members at will to said source of power, shear elements secured to

the periphery of said rotatable members and adapted to coöperate as said members are rotated, and coöperating rolls continuously actuated from said source of power, 5 through which the sheared material passes as it leaves said rotatable members.

6. A rotary shear comprising a frame, a pair of members rotatably supported thereon, a source of power, means for operatively connecting said members at will to said source of power, shear elements secured to the periphery of said rotatable members and adapted to coöperate as said members are rotated, an elongated table to support 10 the material to be sheared, and means thereon to advance said material toward said members while the latter are connected to said source of power.

7. A machine for shearing cold metal comprising a frame, a pair of members rotatably supported thereon, a source of power, means for operatively connecting said members to said source of power at will, shear elements secured to the peripheries of said members and adapted to coöperate as said members are rotated, an elongated table to support the material to be sheared, means thereon to feed the material toward said members when the latter are rotated, and a lost motion connection 25 between said source of power and feeding means.

8. A machine for shearing cold metal comprising a frame, a pair of members rotatably supported thereon, a source of power, means for driving said members from said source of power, shear elements secured to the peripheries of said members and adapted to coöperate as said members are rotated, an elongated table, and means thereon connected to said source of power to advance the material to be sheared toward 30 said members.

9. A machine for shearing cold metal comprising a frame, a pair of members rotatably supported thereon, a source of power, means for driving said members from said source of power, shear elements secured to the peripheries of said members and adapted to coöperate as said members are rotated, an elongated table, means thereon connected to said source of power to feed the material to be sheared toward said members, a support to receive the sheared material from said members, and means thereon and connected to said source of power to prevent the feeding of additional material to said members while material remains on said support.

60 10. A machine for shearing cold metal comprising a frame, a pair of members rotatably supported thereon, a source of power for driving said members, shear elements secured to the peripheries of said members

and adapted to coöperate as said members are rotated, an elongated table to support material to be sheared, means thereon to feed the material toward said members when the latter are rotated, means for operatively connecting said feeding means to 70 said source of power at will, a support to receive the sheared material from said members, and means thereon to prevent actuation of said feeding means while material remains on said support. 75

11. A machine for shearing cold metal, comprising a frame, a pair of members rotatably supported thereon, a source of power, means for operatively connecting said source of power and members at will, 80 shear elements secured to the periphery of said members, an elongated table to support the material to be sheared, means thereon for feeding material toward said members when the latter are rotated, and a pair 85 of coöperating rolls continuously driven from said source of power through which the sheared material passes as it leaves said members.

12. A machine for shearing cold metal, 90 comprising a frame, a pair of members rotatably supported thereon, a source of power, means for operatively connecting said source of power and members at will, shear elements secured to the periphery of 95 said members, an elongated table to support the material to be sheared, means thereon for feeding material toward said members when the latter are rotated, a pair of coöperating rolls continuously driven from 100 said source of power, through which the sheared material passes as it leaves said members, a support for the material as it leaves said rolls, and means thereon to prevent actuation of said feeding means while 105 material remains on said support.

13. A machine for shearing cold metal, comprising a frame, a pair of members rotatably supported thereon, a source of power connected to said members, a plurality of shear elements secured to the peripheries of each of said members and adapted to coöperate as said members are rotated, an elongated table to support material to be sheared, means on said table 110 and driven from said source of power to feed the material to said members, means for initiating the operation of said feeding means at will, a pair of coöperating rolls driven from said source of power to receive 115 the material from said members and a support to receive the material as it leaves said rolls. 120

14. A machine for shearing cold metal comprising a frame, a pair of rotatable members mounted thereon and provided with coöperating shear elements, an elongated table, means thereon to feed material to be sheared 125

- toward said members, a source of power for actuating said members and feeding means, and means for automatically disconnecting said source of power from said members and feeding means at the conclusion of each shearing operation.
15. A machine for shearing cold metal comprising a frame, a pair of rotatable members mounted thereon and provided with coöperating shear elements, an elongated table, means thereon to feed material to be sheared toward said members, a source of power for actuating said members and feeding means, means for automatically disconnecting said source of power from said members and feeding means at the conclusion of each shearing operation, and means preventing reestablishment of the connection between said source of power and said members and feeding means until the sheared material has been removed from the machine.
16. A machine for shearing cold metal comprising a support, a pair of rotatable members mounted thereon and provided with coöperating shear elements, means for receiving material from said rotatable members, means for driving said rotatable members, means for establishing a driving connection between said driving means and rotatable members, means for automatically breaking said connection, and means for preventing the establishment of said driving connection while material remains on said receiving means.
17. A machine for shearing cold metal comprising a support, a pair of rotatable members mounted thereon and provided with coöperating shear elements, means for feeding material to said rotatable members, means for driving said rotatable members and feeding means, means for establishing a driving connection between said driving means and said rotatable members and feeding means, means for automatically breaking such connection, and means for preventing the establishment of said driving connection while material remains on said receiving means.
18. A machine for shearing cold metal comprising a pair of oppositely disposed rotatable members, a plurality of individual shear elements arranged thereon in circumferentially spaced relation, individual thrust plates between each of said elements and the periphery of its supporting mem-
- ber, and means for rigidly securing said shear elements and thrust plates in assembled relation.
19. A machine for shearing cold metal comprising a frame, a pair of members rotatably mounted thereon, and a plurality of sets of circumferentially spaced shear elements of progressively varying length extending about the peripheries of each of said members and adapted to coöperate as said members are rotated to shear in a plurality of parallel lines, the axes of said members being so disposed that the shear elements on the respective members are spaced apart a distance substantially equal to one-half the thickness of the material sheared, at a line joining said axes.
20. A rotary shear comprising a support, a pair of rotatable members mounted thereon, shear elements carried by each of said rotatable members and adapted to coöperate as said members are rotated, coöperating rolls through which the sheared material passes as it leaves said rotatable members, and means for driving said rotatable members at will and for continuously driving said rolls.
21. A rotary shear comprising a support, a pair of rotatable members mounted thereon, shear elements carried by each of said rotatable members and adapted to coöperate as said members are rotated, coöperating rolls through which the sheared material passes as it leaves said rotatable members, means for driving said rotatable members at will and for continuously driving said rolls, and means to support the material as it leaves said rolls.
22. A rotary shear, comprising a support, a pair of rotatable members mounted thereon, shear elements carried by each of said rotatable members and adapted to coöperate as said members are rotated, coöperating rolls through which the sheared material passes as it leaves said rotatable members, means for continuously driving said rolls, means for establishing a driving connection between said driving means and said rotatable members, and means for automatically breaking said driving connection after each rotation of said rotatable members.

ALBERT J. BATES.

Witness:

M. A. KIDDIE.
